CUSHIONING MECHANISM

Emil H. Blattner, Rochester, N. Y., assignor to
The Symington-Gould Corporation, Rochester,
N. Y., a corporation of New York

Original application January 3, 1935, Serial No.
281. Divided and this application July 27,
1938, Serial No. 221,613

7 Claims. (Cl. 213—23)

This is a divisional application of my pending application for Cushioning mechanism, Serial No. 281, filed January 3, 1935.

This invention relates to railway draft rigging and more particularly to the draft gear or cushioning mechanism which forms a part thereof.

An object of the invention is the provision, in a draft rigging, of a double-ended draft gear adapted for series application to provide for a greater buffering than draft energy absorbing capacity.

A feature of the invention is the provision, in a draft gear, of a body member having a slot extending therethrough for the accommodation of a draft key for connecting the body member with associated draft sills, said body member having a twin-arranged means disposed at each end thereof for absorbing the buffering forces applied thereto, only one of said twin-arranged means being actuated during the application of draft forces.

Another feature of the invention is the provision of a cushioning mechanism comprising a body portion having helical spring means engaging one end of the body portion, cooperating segmental friction shoes arranged in pairs and positioned within said spring means, and a central wedge extending from said body member and acting between said friction shoes for urging one pair of shoes into bearing relation with the other pair and the latter into engagement with said helical spring means.

Other objects and features of the invention will become apparent from an inspection of the accompanying drawings which disclose a form of the invention and wherein:

Figure 1 is a partial side elevational view and partial longitudinal vertical section of a form of cushioning mechanism embodying the invention. 40 Figure 2 is a partial end elevational view and partial transverse sectional view of the body member of the form of cushioning mechanism shown in Figure 1; the sectional view being taken along the lines 2—2 of Figure 1, looking in the direction of the arrows.

Figure 3 is a fragmentary transverse sectional view taken on the line 3—3 of Figure 1, looking in the direction of the arrows.

Figure 4 is a plan view of one of the inner spring plates.

Figure 5 is a partial elevational view and partial sectional view of Figure 4, the sectional view being taken along the lines 5—5 thereof, looking in the direction of the arrows.

55. Figure 6 is a side view of one of the outer

segmental friction shoes removed from the associated parts.

Figure 7 is an end view of the shoes shown in Figure 6.

Figure 8 is a side view of one of the inner segmental friction shoes separated from the associated parts.

Figure 9 is an end view of the shoe of Figure 8.

Figure 10 is a plan view of one of the outer 10 spring plates.

Figure 11 is a sectional view taken along the lines 11—11 of Figure 10.

Referring now to the drawings in detail, there is shown an embodiment of a cushioning mechanism 1a, comprising a body member or casting 2a having a pair of helical or coil spring barrels 3a twin-arranged and disposed at either end thereof. The body member or casting 2a desirably has a longitudinally disposed slot, as indicated at 4a, for receiving a draft key or other stop means (not shown) in order to connect the body member to associated draft sills (not shown). The gear 1a may have a front follower 7a and a rear follower 8a associated with the front and rear faces thereof, and the gear may also be normally disposed between the arms and rear portion of a draft yoke (not shown) as well as a coupler stem (not shown).

Inasmuch as the spring barrels 3a and associated mechanism are identical in all respects 30 and in all of the arrangements at both ends of the body member 2a, only one of said arrangements will be hereinafter described.

A helical spring barrel 3a is desirably formed 35 of bar material of a rectangular or square cross section and has a cylindrical inner surface 5. Each helical spring barrel reacts longitudinally of the mechanism between an outer spring plate or seat 12a and an inner spring plate or seat 13a. The face of the outer spring seat 12a, outwardly 40 of or away from the helical spring 3a, is provided with a recess 22a to accommodate outstanding flanges 14a on a pair or set of outer segmental 45 counterpart friction elements or shoes 15a, thereby disposing the outer surfaces of the flanges 14a and the outermost surface of the outer spring seat 12a in substantially a common plane to form an adequate area for the arrangement to bear against the follower 7a or 8a, as the case may be.

By extending into the recess 22a the outer shoe 50 flanges 14a form an interlock between the outer shoes and outer spring plate, thereby allowing the spring barrel to urge the outer shoes outwardly of the mechanism or away from the body member 2a during an expansive movement of the 55

- helical springs. As will be noted by referring to Figure 10 of the drawings, the recess 22^a is formed to prevent axial rotation between the outer shoes and outer spring plate. The outer set of shoes 12^a is arranged with cylindrically disposed surfaces 6 which frictionally engage the inner cylindrical surface 5 of the helical spring barrel 3^a upon a compressive or expansive movement of the mechanism.
- 10 The complementary set of inner segmental counterpart friction elements or shoes 16^a has outer surfaces 9 thereof in bearing relation with inner faces 10 of the shoes 15^a. The surfaces 9 and 10 are desirably generally cylindrical and 15 have corresponding curvatures in horizontal cross section, as most clearly illustrated in Figure 3, to present engaging surfaces of appreciable area between the shoes 15^a and 16^a. Both the surfaces 9 and 10 are substantially slightly inclined 20 inwardly of the draft gear toward the body member 2^a or angularly disposed to the longitudinal axis of the associated spring. The inner shoes are provided at their inner or the body adjacent ends with outstanding radial flanges 17^a which 25 extend into a relief or recess 21^a of the inner spring seat 13^a to overlap a portion of or interlock with the spring seat. As most clearly illustrated in Figure 4 of the drawings, the recess 21^a is formed in the inner spring seat so as to prevent 30 relative axial rotation between the inner spring seat and inner friction shoes 16^a.
- A central thrust post or wedge member 18^a, in the present embodiment, is formed as an integral projection extending outwardly of the body member toward the end of the mechanism. The wedge member 18^a, which forms a means for retaining the associated spring barrel and shoes in a predetermined position with respect to the body member 2^a, extends between the inner and outer friction shoes, as most clearly illustrated in Figures 1 and 3 of the drawings. The central wedge 18^a has oppositely disposed plane faces 19^a thereof in spaced relation to the body member 2^a and inclined to the longitudinal axis of the associated 40 spring barrel. The inclined faces 19^a are normally in bearing relation with complementarily formed wedging faces 23^a on the inner shoes 16^a positioned intermediate the ends of said shoes so that when the cushioning mechanism is compressed the particularly disposed and engaging surfaces 19^a and 23^a will provide for a spreading movement of the inner shoes 16^a to increase the radial pressure exerted against the outer shoes 15^a and correspondingly increase the radial pressure exerted against the inner surface 5 of the helical spring barrel. The wedge member or integral post 18^a is laterally elongated in horizontal cross section, as most clearly illustrated in Figure 3 of the drawings, and desirably extends approximately across the chamber of the spring barrel 3^a interfitting between the segments of the shoes 15^a and 16^a to thereby prevent an undesired rotative movement of said shoes with respect to the wedge member and one another.
- 55 In order to hold the above-described associated elements of the mechanism assembled, as well as limit outward or longitudinal movement of the assembled structure away from the body member 2^a, the outer spring plate 12^a is connected to the integral post 18^a by means of an axially disposed bolt 26^a. The bolt 26^a may be of conventional form with an integral head 27^a at its inner or post adjacent end and an element or nut 28^a threaded or detachably secured to the free or outer end.
- 70 75 In order to provide for an over-solid force or

load during service and reinforce or stiffen the relatively thin section of the body member 2^a at the ends of the key slot 4^a, there is desirably provided a necked down projection 33 centrally disposed of the mechanism and formed integral with the body member. The projection 33 extends between the twin-arranged helical spring barrels on each end of the body member 2^a, as most clearly illustrated in Figures 1 and 2 of the drawings, and is provided with cylindrically formed surfaces 34 positioned in the close proximity of the associated spring barrel to form guiding surfaces for the spring barrels and associated parts.

It will be noted that while a preferred embodiment of the invention has been illustrated in the various figures of the drawings and described by the present specification, numerous changes and alterations may be made thereto without departing from within the spirit and scope of the appended claims.

I claim:

1. Cushioning mechanism comprising a body portion, twin-arranged helical spring barrels engaging one end of said body portion, a seat for each end of each spring barrel, cooperating segmental friction shoes arranged in pairs within each spring barrel, the members of each pair being anchored to said seats respectively disposed adjacent said body member, and at the end of the mechanism away from said member, a central wedge member integral with and extending from said body member into each spring barrel and acting between said friction shoes for urging them laterally and pressing them together, said central members being in wedging engagement with one pair of friction shoes, and means for holding the parts of the mechanism assembled.

2. Cushioning mechanism comprising a body portion, twin-arranged helical spring barrels disposed at each end of said body portion, a seat for each end of each spring barrel, cooperating segmental friction shoes arranged in pairs within each spring barrel, the members of each pair being anchored to said seats respectively disposed adjacent said body portion and at opposite ends of the mechanism, pairs of central wedge members integral with said body portion and extending outwardly therefrom with one received into each spring barrel, and acting between said friction shoes for urging them together, said central members being in wedging engagement with one pair of friction shoes, and means for securing the outer spring seats to said central wedge members for holding the parts assembled.

3. A cushioning mechanism comprising a body portion, twin-arranged spring barrels engaging one end of said body portion, a seat for each end of each spring barrel, cooperating segmental friction shoes arranged in pairs within each of said barrels, the shoes of each pair being interlocked with said seats respectively disposed adjacent said body member and at one end of the mechanism away from said member, a central wedge member formed integrally with and extending from said body member into each spring barrel and acting between pairs of said friction shoes for urging them laterally and pressing said shoes together, said central members being in wedging engagement with one pair of friction shoes, removable means for holding the parts of the mechanism together, and means associated with said body member and extending between said spring barrels to prevent excessive load applications to said springs.

4. Cushioning mechanism comprising a body

20

portion, twin-arranged helical spring barrels engaging one end of said body portion, a seat for each end of each spring barrel, cooperating segmental friction shoes arranged in pairs within each of said spring barrels, the members of each pair being anchored to said seats respectively disposed adjacent said body member, and at the end of the mechanism away from said member, a central wedge member integral with and extending from said body member into each spring barrel and acting between said friction shoes for urging them laterally and pressing them together, said central members being in wedging engagement with one pair of friction shoes, and means formed integral with said body member and extending between said spring barrels to prevent excessive load applications to said springs.

5. A cushioning mechanism comprising a body portion, twin-arranged spring barrels engaging one end of said body portion, a seat for each end of each spring barrel, cooperating segmental friction shoes arranged in pairs within each spring barrel, the shoes of each pair being interlocked with said seats respectively disposed adjacent 25 said body member and at one end of the mechanism away from said member, a central wedge member formed integrally with and extending from said body member into each spring barrel and acting between said friction shoes for urging them laterally and pressing them together, said central members being in wedging engagement with one pair of friction shoes, and means associated with said body member and extending between said spring barrels, said means having 30 cylindrically concave surfaces for engagement by said spring barrels to form guide means for said barrels.

6. Cushioning mechanism comprising a body portion having a slot extending therethrough for

the reception of a draft key, twin-arranged helical spring barrels engaging one end of said body portion, an inner and an outer seat associated with the ends of each of said spring barrels, cooperating inner and outer friction shoes arranged 5 in pairs within each of said spring barrels, the outer shoes and inner shoes being interlocked with said outer and inner seats, respectively, a central wedge member formed integrally with and extending from said body member into each 10 spring barrel, said central wedges acting between said inner shoes for urging them into engagement with said outer friction shoes and said outer friction shoes into engagement with said spring barrels, and means for securing the outer spring 15 seat to said central wedge members for holding the mechanism assembled.

7. Cushioning mechanism comprising a body portion having a slot extending therethrough for the reception of a draft key, twin-arranged helical spring barrels engaging one end of said body portion, an inner and an outer seat associated with the ends of each of said spring barrels, cooperating inner and outer friction shoes arranged 20 in pairs within each of said spring barrels, the outer shoes and inner shoes being interlocked with said outer and inner seats, respectively, a central wedge member formed integrally with and extending from said body member into each 25 spring barrel, said central wedges acting between 30 said inner shoes for urging them into engagement with said outer friction shoes and said outer friction shoes into engagement with said spring barrels, and means formed integrally with said body 35 member and extending between said spring barrels, said means having cylindrically concave surfaces for guiding said spring barrels during movements thereof.

EMIL H. BLATTNER.
